UNITED STATES PATENT OFFICE.

HERBERT M. HAINLINE, OF SCIOTA, ILLINOIS.

COMBINATION LOCK.

1,420,483.

Specification of Letters Patent. Patented June 20, 1922.

Application filed October 27, 1921. Serial No. 510,718.

To all whom it may concern:

Be it known that HERBERT M. HAINLINE, a citizen of the United States of America, residing at Sciota, in the county of McDonough and State of Illinois, has invented new and useful Improvements in Combination Locks, of which the following is a specification.

The object of the invention is to provide 10 a simple, relatively inexpensive and efficient combination lock adapted for general purposes but designed especially for use in securing a motor meter in place against surreptitious or accidental displacement or removal, such motor meter as in the ordinary 15 practice being carried by the cap of an automobile radiator and being subject to displacement by the vibration of the vehicle and of misplacement and loss by neglect to 20 return the same to its proper position after removal for the introduction of water into the radiator system; and with this object in view the invention consists in a construction 25 and combination of parts of which a preferred embodiment is shown in the accompanying drawings, wherein:

Figure 1 is an elevation partly broken away of a lock mechanism embodying the invention applied to a motor meter.

Figure 2 is a sectional view of the same taken on the plane at right angles to that of Figure 1.

Figures 3, 4 and 5 are transverse sectional views taken respectively on the planes indicated by the lines 3—3, 4—4 and 5—5 of Figure 2.

Figure 6 is a plan view of the bearing or assembling sleeve or thimble.

Figures 7 and 8 are side views in detail 40 respectively of the bearing or assembling sleeve and the core.

Figure 9 is a detail view of the locking pin.

Figure 10 is a detail view in section of a 45 modified construction of core having the locking lugs constructed as ratchet teeth to facilitate insertion or movement to the locking position.

Figures 11 and 12 are respectively plan 50 and sectional views of a modified spacing disk for use in connection with the construction shown in Figure 10.

The lock consists essentially of a plurality 55 of revolute tumbler disks 10 between which are arranged spacing disks 11 held in assembled relation by a terminally flanged

thimble or sleeve 12 and all arranged in a casing 13 which constitutes the plug or cap of the radiator and is exteriorly threaded for engagement with the threads in the opening thereof, the disks 10 being of such a diameter relative to the interior of the casing as to permit of access to the peripheries of the disks from the open inner side of the casing to adjust the disks rotatably in 60 the operation of the lock. The disks are peripherally notched as indicated and the sleeve or thimble is provided with radial lugs 15 engaging suitable notches 16 in the inner peripheries of the spacing disks. A 65 core 17 is carried by the stem 18 of the motor meter 19, said stem being the element which in the use of the device performs the function of a bolt of which the position controls the movement of a latch pin 20 70 which must be displaced after proper adjustment of the locking mechanism in order to permit of the disengagement of the latch pin and the removal of the plug from the 75 machine.

In the construction illustrated the latch pin is provided with reduced neck portions 21 adapted for engagement with keyhole slots 22 in a barrel 23 which constitutes the stopper to fit in the filling opening of a 80 radiator tank, and the normal position of the stem or bolt 18 with relation to the barrel 23 is such as to obstruct the movement of the latch pin and prevent its registration with the enlarged portions of the keyhole 85 slots and therefore prevent its disengagement from the barrel. The latch pin is adapted for engagement with the terminal link of a retaining chain 24 which, by extending into and being anchored within the 90 tank serves to permanently connect the lock mechanism and the motor meter carried thereby to the tank although permitting of the removal of the barrel from the filling opening sufficiently to enable the tank to 95 be supplied. In order to disconnect the motor meter from the machine it is necessary to manipulate the lock and withdraw the stem or bolt 18 sufficiently to permit of the registration of the latch pin 20 with the 100 enlarged portions of the keyhole slots in the barrel.

In the construction illustrated the stem or bolt 18 is threaded into engagement with the core 17 and the engagement is of a sufficiently rigid character to prevent displacement of the former from the latter, and car- 110

ried by the core is a series of lugs 25 extending through a slot 26 in the sleeve or thimble 12 for engagement with the notches 27 in the inner peripheries of the several 5 tumbler disks. When the notches of the tumbler disks are out of alignment with the lugs 25 it is obvious that axial or longitudinal movement of the stem or bolt 18 and the core carried thereby is prevented by the 10 engagement of said lugs 25 with the under surfaces of the tumbler disks; whereas by a proper adjustment of the tumbler disks to register the notches 27 thereof with the lugs 25 a longitudinal or axial movement of the 15 core is permitted sufficient to withdraw the inner end of the stem or bolt from the path of movement of the latch pin to allow of the disengagement of the latter from the barrel.

20 In the construction illustrated the outer peripheries of the tumbler disks are notched to provide finger holds so that they may be properly manipulated.

In the modified construction illustrated 25 in Figures 10 to 12 inclusive the lugs or teeth 25^a on the core 17^a are yieldingly mounted by means of a plate 25^b held in place by a spring 25^c, and the spacing disks 11^a are flanged as shown at 11^b to provide 30 clearance so that after the bolt or stem has been withdrawn it may be returned to locking position after a readjustment of the tumbler disks should they have become disarranged during the unlocked condition of the 35 device to remove the notches 27 thereof from their position in registration with the lugs of the core.

Moreover in the construction illustrated it will be noted that the barrel 23 is provided 40 with an inwardly flanged upper end as shown at 27' for engagement with the lower flange 28 of the sleeve or thimble 12.

Whereas it is preferable as illustrated in 45 the drawing to provide the upper end of the barrel 23 with an inturned flange, it will be understood that the mechanism is susceptible of a modification in this respect to the extent of making the same either fast or separate.

50 Furthermore it should be noted that the lock as described can not be removed with a wrench or otherwise until the parts are separated as the barrel and tumbler disks turn freely around the assembling sleeve and core and can not be unscrewed until these parts are taken off.

Having described the invention, what is claimed as new and useful is:—

1. A combination lock having an axially 60 movable stem or bolt and associated tumbler disks for locking the same against axial movement, and a sleeve by which said disks

and bolt are carried, in combination with a barrel for interlocking engagement with one end of said sleeve and provided at diametrically opposite points with longitudinal key hole slots transversely intercepted by the terminal of said bolt when in its normal position, and a latch pin engaged in said key hole slots. 65

2. A combination lock having a plurality of revoluble tumbler disks and interposed spacing disks, a terminally flanged thimble or sleeve upon which the tumbler disks are mounted and which has an interlocking engagement with the spacing disks, and an axially movable stem or bolt having a core fitted in said sleeve or thimble and provided with radial lugs projecting through a slot in the sleeve or thimble for passage through 80 notches formed in the inner peripheries of the tumbler disks, in combination with a barrel having opposite keyhole slots and a latch pin fitted in said slots, said stem or bolt being normally arranged in the path 85 of movement of the pin in the slots. 70

3. A combination lock having a plurality of revoluble tumbler disks and interposed spacing disks, a terminally flanged thimble or sleeve upon which the tumbler disks are 90 mounted and which has an interlocking engagement with the spacing disks, and an axially movable stem or bolt having a core fitted in said sleeve or thimble and provided with radial lugs projecting through a slot 95 in the sleeve or thimble for passage through notches formed in the inner peripheries of the tumbler disks, said stem or bolt carrying a motor meter and having a threaded engagement with said core. 100

4. A combination lock having a plurality of revoluble tumbler disks and interposed spacing disks, a terminally flanged thimble or sleeve upon which the tumbler disks are mounted and which has an interlocking engagement with the spacing disks, and an axially movable stem or bolt having a core fitted in said sleeve or thimble and provided with radial lugs projecting through a slot in the sleeve or thimble for passage through notches formed in the inner peripheries of the tumbler disks, a casing being arranged in enclosing relation with the said disks, in combination with a barrel for interlocking engagement with one 110 end of said sleeve or thimble and provided at diametrically opposite points with longitudinal keyhole slots transversely intercepted by the terminal of said stem or bolt when in its normal position and a latch pin engaged with said keyhole slots. 115

In testimony whereof he affixes his signature.

HERBERT M. HAINLINE.
